ATTORNEY.

UNITED STATES PATENT OFFICE

RHYS DAVIES, OF FORT WAYNE, INDIANA

ELECTRICAL HEATER

Application filed October 19, 1928. Serial No. 312,448.

The invention relates to electrical heaters therewith of a cord circuit. The resistance wire is secured to the section 2 in a predetermined manner as shown in Fig. 3. The outer winding 6 follows substantially around the rear margin of the section and at a selected distance therefrom. It is then curved over the chin portion 7, the cheek 8, the temple 9, the forehead 10, and the opposite temple and cheek. By curving the element as shown there are two turns of the same on the forehead and on the cheeks and one on the chin and one under the chin. 55

It is frequently beneficial to apply heat to a selected part of the body to aid circulation or to open the pores of the skin and it is an advantage and more effective in many instances to have the heating appliance conform to the shape of the part to be heated. In facial treatments especially I have found that a heating appliance that will cover the face and conforms to its contour is most efficient. 10

The object of the invention is to provide a novel electrical heater that conforms to the contour of the part of the human body to be heated, the heat generated by the appliance being distributed uniformly over the said part the heater being applied with a maximum of ease. 15

Another object is to provide a heater in which the heating element is arranged in a novel manner. 20

One form of the invention is illustrated in the accompanying drawings in which

Figure 1 is a plan view of the heater in the form of a mask for application to the human face; Fig. 2 a side elevation of the same; Fig. 3 a plan view of the heater with the front coverings removed and Fig. 4 a cross-section on line 4—4 on Fig. 3.

In the illustrative embodiment of the invention the heater consists of two sections 1 and 2 (Fig. 4) which are formed of suitable moldable material such as rubber or papier mâché, the latter material being shown in the illustrative heater. The sections 1 and 2 and a similar covering 4 is secured to the A suitable sanitary covering 3 is preferably secured to the outer or rear face of the section 2 and a similar covering 4 is secured to the outer face of the section 1. Both or either of 45 said coverings 3 and 4 may be omitted.

The heating element 5 is preferably a length of resistance wire covered with asbestos, the opposite ends of the wire being exposed at the rear edge of the mask or accessible adjacent said edge for the connection

spacing members are provided on the section 2 to space it from the section 1. A simple and light material for such members is corrugated paper. A strip 11 of such material is secured to the section 2 between the outer turn 6 of the heating element and the edge of the section. Another strip 12 is disposed between the turn 6 and the turn 13 on the forehead portion and other strips 14 are disposed on the cheek portion between the turn 6 and the S-turns 15 on said cheek portions. The sections 1 and 2 together with their coverings, when such are employed, are suitably secured together as by a binding strip 16. 65

The heat generated by the heating element is therefore generated at the desired points and is distributed over the face through the space between sections 1 and 2. 70

An opening or slot 17 extends through the entire appliance through which the user may breathe. The nose section 18 comfortably receives the nose of the user so that the inner surface of the appliance may snugly engage the face and be readily held thereon with one hand whether the user is standing, reclining or prostrate. 75

It is evident that the appliance may be made in various shapes and that it may be more or less elastic to insure complete contact with the surface to be heated. Any suitable means for spacing the two molded sections will suffice. 80

What I claim is:

An electrical heater consisting of a mask having two molded walls of insulating material molded to fit the human face, corrugated strips between the walls to space the same and 100

form radial channels between them and a heating element wound in a circuitous path between the opposed edges of the strips to heat the said walls uniformly throughout 5 their area.

In witness whereof I have hereunto set my hand.

RHYS DAVIES.
